UNITED STATES PATENT OFFICE

2,602,952

CARPET HOLDING DEVICE

Jesse C. Owens, Los Angeles, Calif.

Application August 30, 1948, Serial No. 46,773

3 Claims. (Cl. 16—16)

1

My invention relates to carpet laying and holding devices and included in the objects of my invention are:

First, to provide a device of this character which may be incorporated in many of the tools and fittings employed in laying or holding carpets; for example, in "Knee Kickers," "Pole Stretchers," "Stay Tackers," drying and stretching frames, display racks and marginal securing strips.

Second, to provide a device of this class which involves a tooth or prong member of novel form so arranged as to engage the backing of a carpet without damage to the pile.

Third, to provide a device of this class which is particularly adapted for incorporation in knee kickers, or pole stretchers of the type disclosed in my prior Patent No. 2,184,019 issued December 19, 1939, entitled Carpet Stretcher.

Fourth, to provide a device of this character which, when incorporated in marginal strips affords an invisible means for securing the edge of the carpet, whether such edge is covered by a base mold or the base mold is omitted.

Fifth, to provide on the whole a novelly constructed marginal strip which permits the edge of the rug to be doubled upon itself, not only to strengthen the edge, but also to insure a smooth and attractive finish.

Sixth, to provide a marginal strip which incorporates its own means for fastening to an underlying surface whether such surface be wood flooring or composition material applied to the margin of the floor.

Seventh, to provide a marginal strip which may be arranged to hold and retain the margins of underpadding as well as the carpet itself.

With the above and other objects in view, as will appear hereinafter, reference is directed to the accompanying drawings, in which:

Figure 1 is a side view of a knee kicker incorporating my novel carpet engaging device.

Figure 2 is a bottom view thereof with a portion of the spacer plate broken away.

Figure 3 is an enlarged fragmentary sectional view through 3—3 of Figure 1.

Figure 4 is an enlarged fragmentary view of the base plate incorporating my novel carpet engaging prong.

Figure 5 is a sectional view thereof taken through 5—5 of Figure 4.

Figure 6 is a fragmentary sectional view showing flooring, an adjacent wall, underpadding, a carpet and a marginal strip incorporating my invention.

Figure 7 is a fragmentary plan view of my marginal strip.

Figure 8 is a fragmentary side view thereof.

Figure 9 is similar to Figure 6 but shows an alternative form of marginal strip incorporating my invention.

Figure 10 illustrates my invention adapted to

2

use as a carpet hanger employed for the purpose of drying or displaying carpets.

Figure 11 is an enlarged view taken from 11—11 of Figure 10 with the carpet removed illustrating the clamping jaws employed to hold the carpet.

Figure 12 illustrates my invention as applied to a carpet drying frame.

Figure 13 is a bottom view of a carpet stretcher and stay tacker incorporating my invention.

10 Reference is first directed to Figures 1 to 5, inclusive. The structure here shown is known commercially as a "Knee Kicker." Such tool includes a tube 1 having a head member 2 defining a flat rectangular or square undersurface, preferably slightly recessed, to receive a base plate 3 secured by screws 4. The base plate is provided with a plurality of special prong elements 5 which are stamped from the material of the base plate and bent at right angles thereto. The construction of these prong elements constitutes an important part of my invention and will be described in more detail hereinafter.

20 A spacer plate 6 having slots 7 therein to clear the prong elements is attached to the head member 2 by adjustment screws 8. The adjustment screws 8 are rotatively mounted in the plate and threaded in the head. Preferably these screws are accessible from the top of the head member so that the spacer plate may be adjusted to regulate the extent to which the prong elements protrude.

25 The knee kicker includes a stem 9 which fits in the tube 1 and which receives a ferrule 10. The ferrule is designed to hold and secure a pad structure 11 designed to be engaged by one's knee.

30 Reference is now directed to Figures 6 to 8, inclusive. The construction here shown illustrates the application of my novel carpet engaging prong element to a marginal strip 21. Marginal strips are placed adjacent the base board of a room for the purpose of securing the margins of a carpet. My marginal strip 21 is formed of sheet metal from which is stamped a series of prong elements 5 as in the first described structure. Also stamped from the marginal strip and bent in the opposite direction from the prongs 5 are securing teeth 22 and 23. The teeth 22 are shown as disposed in planes at right angles to the prongs 5 whereas the teeth 23 are shown as disposed in planes parallel to the prongs 5.

35 The prong elements 5 are specially formed to provide an improved carpet engaging function. The forward edge 24 of each prong curves forwardly and may be termed a bearing edge. Near its extremity it is provided with a rounded notch 25. Beyond the notch 25 the prong terminates in a sharp point 26. The rear edge of the prong is essentially S-shaped so as to improve the form of the point 26 and enable it to penetrate readily through the backing of a carpet such as the backing B shown in Figure 6. Whether the prong is used in the knee kicker or in the marginal strip,

it is intended that the point penetrate the backing B of a carpet C until the notch 25 is essentially coplanar with the backing. When in this position the prong may engage the strip of carpet without having to force the carpet either toward the point or towards the base of the prong. When the prong is used in the knee kicker or similar device the spacer plate 6 is adjusted so that the notches 25 of the several prongs will engage the carpet backing when the spacer plate rests on the pile P of the carpet.

When the prong is employed in the marginal strip its proportions are such that the notch 25 engages the backing B. It is customary to use subpadding S which raises the backing to an appropriate height for engagement by the notch 25 when the marginal strip is fastened to the flooring. In such cases it is convenient and highly desirable to fold the margin of the carpet, in which case the prongs are forced through two thicknesses of the carpet and thus insure proper and dependable engagement so that there is no danger of the carpet pulling loose. In practice the carpet is placed over the prongs and a rubber mallet is employed to drive the carpet downwardly thereover.

Reference is now directed to Figure 9. In this construction a marginal strip 31 is employed in which are formed major prongs 32 and minor prongs 33. The minor prongs are sufficiently short to engage the reinforcing of the subpadding S whereas the major prongs are high enough to engage the carpet backing B. As an alternative the marginal strip 31 is shown fastened by nails 34. However, the teeth 22 or 23 may be employed. Furthermore, it is preferred to stagger the prongs in the manner shown in the base plate 3 of the knee kicker.

The marginal strip 21 or 31, or a variation thereof, may be employed for other purposes; for example, it may be incorporated in a rug hanging or display structure such as shown in Figures 10 and 11. In this case a marginal strip 41 is provided with two rows of staggered prongs 5 of equal length. The marginal strip is fastened to a mounting bar 42 which in turn is secured to a jaw of a tong structure 43. The opposite jaw may be provided with a second marginal strip 44 which may have prongs 5, but preferably is provided with rounded tongues 45 designed to bear against but not penetrate the backing. It is preferred to mount a carpet or rug so that the pile faces the tongues 45. The tongues are thus capable of penetrating the pile without crushing or damaging the strands of the pile. The tong structure 43 may be supported on a suitable arm 46 adjustably mounted on a pole 47.

Reference is directed to Figure 12 which illustrates diagrammatically that the marginal strips, such as the marginal strip 41, may be incorporated in a frame structure 48 designed to engage the margins of a rug or carpet for the purpose of holding its form while drying.

Reference is now directed to Figure 13, which is a substantially diagrammatical bottom view of a carpet stretcher and stay tacker more fully disclosed in my copending application mentioned hereinbefore.

A "Pole Stretcher" comprises a pair of head members 51 and 52 which are adapted to be connected by a sectional pole structure 53 which incorporates a lever means (not shown) for the purpose of advancing one of the head members relative to the other. In order to enable such head member to be released without relieving the 75

stretch in the carpet, a "Stay Tacker" 54 is provided on the pole structure which engages the carpet until a new "bite" is obtained. The carpet engaging elements of the heads 51 and 52, as well as the stay tacker, may be essentially the same as shown on the knee kicker in Figures 1 to 5 inclusive; that is, my prong elements 5 are incorporated therein in a manner similar to that of Figures 1 to 5 and spacer plates similar to the spacer plate 6 are employed to regulate the depth of penetration of the prongs.

Having fully described my invention, it is to be understood that I do not wish to be limited to the details herein set forth, but my invention is of the full scope of the appended claims.

I claim:

1. A carpet engaging marginal strip comprising: a base strip of sheet metal adapted to underlie a margin of a rug; integral sheet metal prongs bent upwardly from said base strip and adapted to penetrate a folded margin of a carpet to engage and bear edgewise with the underlying and overlying portions of the backing of said carpet; each of said prongs being tapered to a point, one edge being obtusely inclined, smooth-edged, convex at its root portion and concave at its extended portion, the other edge being acutely inclined, concave at its root and having a carpet-backing retainer notch adjacent its extremity.

2. A means for securing the margins of a carpet and underlying pad, comprising: a strip of sheet metal; minor prongs bent upwardly from said strip and adapted to penetrate the margin of said underlying pad; and major prongs also bent upwardly from said strip and adapted to penetrate the margin of said carpet projecting beyond said pad; each of said major and minor prongs being tapered to a point, one edge being obtusely inclined, smooth-edged, convex at its root portion and concave at its extended portion, the other edge being acutely inclined concave at its root and having a carpet-backing retainer notch adjacent its extremity.

3. A carpet engaging device, including: a sheet metal plate adapted to confront a surface of a carpet; a plurality of integral prong members extending from said plate and edgewise inclined, each of said prongs being tapered to a point, one edge being obtusely inclined, smooth, convex at its root portion and concave at its extended portion; the other edge being acutely inclined, concave at its root end and having a carpet-backing retaining notch adjacent its extremity.

JESSE C. OWENS.
